A. Faber du Faure ATTORNEY

UNITED STATES PATENT OFFICE.

EDWARD G. SOLTMANN, OF NEW YORK, N. Y.

TAPE-MEASURE.

SPECIFICATION forming part of Letters Patent No. 406,065, dated July 2, 1889.

Application filed April 22, 1889. Serial No. 308,057. (No model.)

To all whom it may concern:

Be it known that I, EDWARD G. SOLTMANN, a citizen of the United States, and a resident of New York, in the county and State of New York, have invented a new and useful Improvement in Tape-Measures, of which the following is a specification.

My invention relates to improvements in tape-measures; and it consists, essentially, in combining with the reel-handle a movable finger-piece, and also in providing means for rigidly securing the finger-piece, as fully pointed out in the following specification and claims, and illustrated in the accompanying drawings, in which—

Figure 1 represents a plan view of a tape-measure embodying my invention. Fig. 2 is a side elevation of the same. Fig. 3 is a sectional elevation of the reel-handle and its attached finger-piece. Fig. 4 is a plan or face view of the finger-piece detached. Fig. 5 is a plan view of a tape-measure, illustrating a different method of securing the finger-piece to the reel-handle. Fig. 6 is a sectional elevation of the reel-handle and a finger-piece, as shown in Fig. 5, attached thereto. Fig. 7 is a plan or face view of the said finger-piece detached.

Similar letters of reference indicate corresponding parts.

In the drawings, the letter A designates the casing.

B is the tape, C the reel, and D the hinged reel-handle, said parts constituting a tape-measure of a well-known construction.

E is the finger-piece, which, as shown in Figs. 1, 2, 3, and 4, is provided with a longitudinal slot *a*, and secured to the reel-handle D by screws *b* and *c* passing through the slot.

When the heads of the screws are out of contact with the finger-piece, or bear lightly upon the same, said finger-piece can be drawn in

or out, so as to adjust the leverage to the difficulty experienced in swinging open the hinged reel-handle. If desired, the screws 45 can be tightened up after such adjustment to retain the finger-piece firmly in its adjusted position.

In Figs. 5, 6, and 7 I have illustrated another method of securing the finger-piece to 50 the reel-handle. In this case the finger-piece E' can turn about a pivot *b'* at or near its inner end, so as to bring it entirely within the periphery of the reel-handle when not in use. It can be secured when in its outer position 55 by a screw *c'*, the end of which engages a threaded recess *d*, or a simple recess formed in the reel-handle.

What I claim as new, and desire to secure by Letters Patent, is—

1. In a tape-measure, the combination, with the reel-handle, of a movable finger-piece, substantially as described.

2. In a tape-measure, the combination, with the reel-handle, of an adjustable finger-piece, 65 and means for rigidly securing the same to the reel-handle, substantially as described.

3. In a tape-measure, the combination, with the reel-handle, of a finger-piece provided with a longitudinal slot and screws for securing the finger-piece to the reel-handle, substantially as described.

4. In a tape-measure, the combination, with the reel-handle, of a movable finger-piece and means for rigidly securing the same to the 75 reel-handle, substantially as described.

In testimony that I claim the foregoing as my invention I have signed my name, in presence of two witnesses, this 18th day of April, 1889.

EDWARD G. SOLTMANN.
